Attorney

the object to be gripped between the jaw 11 and the anvil 12.

To use the tool as a gripping wrench or vise the handle knob 42 will be adjusted so that when the movable handle 27 is pressed upwardly the pivot pin 37 will pass beyond the dead center to produce a powerful locking grip action upon the work piece. The spring 32 will then serve to hold the toggle link 36 in contact with the pin 40.

While there has been disclosed in this specification one form in which the invention may be embodied, it is to be understood that this form is shown for the purpose of illustration only, and that the invention is not to be limited to the specific disclosure, but may be modified and embodied in various other forms coming within the scope of the following claim.

Having thus fully described the invention, what is claimed as new, and for which it is desired to secure Letters Patent, is:

In a work-engaging jaw for a tool, an anvil

comprising a pair of opposed abutting strips of metal secured together and having wedge-shaped work-engaging sections provided with a pair of outturned integral flanges lying in a common plane, each flange forming a work-engaging face, the abutting surfaces of said opposed strips diverging outwardly from a line below the common plane of the work-engaging faces of said flanges, whereby a longitudinal work-gripping groove is formed between said flanges.

LOUIS E. ISELE.
